UNITED STATES PATENT OFFICE

2,524,455

MOUNT ASSEMBLY FOR SUN LAMPS

Michel E. Macksoud, Newburyport, Mass., assignor to Cooper-Hewitt Electric Company, Hoboken, N.J.

Application February 19, 1948, Serial No. 9,558

1 Claim. (Cl. 176—122)

1

This invention relates to improvements in an assembly of component elements of electric lamps which includes a mercury arc discharge tube, and particularly, to an improved mount assembly, for supporting the various lamp components included in the construction of the present day sun lamp.

It is, accordingly, an object of the present invention to provide a compact, efficient sun lamp assembly within a bulb having a reflecting surface, so as to obtain, in cooperation with the reflecting surface, a sun lamp having a uniformly blended pattern of radiation within the defined area produced by the reflector.

In sun lamps of this type, the usual practise is to provide a mount assembly which includes a mercury arc discharge tube supported by spaced metallic discs, together with a ballast filament which is mounted at the extreme end of this assembly. These two principal elements of a modern sun lamp, mainly the mercury arc discharge tube and the series connected ballast filament, are usually mounted within the bulb adjacent to the focal point of the reflecting surface of the bulb.

A particular feature of this invention resides in a refinement of the positioning of the two principal functioning elements of a modern sun lamp, namely the mercury arc discharge tube and the series connected ballast filament, so that these elements are as close as possible to the center of the focusable area of the reflecting surface of the bulb, in order to direct uniform and blended ultra-violet and infra-red radiations of the lamp upon an exposed object.

Another feature of this invention is the separation of the ballast filament into two or more sections, mounted closely adjacent and parallel to the longitudinal axis of the mercury arc discharge tube, which brings more closely together these two sources of radiation within the focusable area of the sun lamp bulb reflector, and thus considerably improves the efficiency of the lamp as well as reduces the stabilization time required for optimum radiation transmission characteristics.

Another object of this invention is to utilize the heat produced by the ballast filament when incandescent, in order to reduce the time factor necessary for the arc tube to reach maximum operating characteristics, and maximum efficiency.

A still further object of this invention is to provide a rigid support for the mercury arc discharge tube and the series connected ballast fila-

2

ment which considerably simplifies and strengthens the sun lamp mount assembly.

Reference is made to U.S. Patent No. 2,171,580 and U.S. Patent No. 2,277,876, both issued to Michel E. Macksoud, which include structural means for disposing the ballast filament as close as possible to the mercury arc discharge tube, both elements being mounted within the focusable area of the reflector of the sun lamp bulb. However, a particular object of this present invention is a still further refinement of the structural details of the assembly for the ballast filament constituting an improvement which makes the entire mount assembly more feasible from a commercial production point of view.

Since this new and novel mount assembly construction establishes and positions the combined two sources of radiant energy; namely, the ultra-violet radiations generated by the mercury arc discharge tube and the infra-red radiations generated by the incandescent ballast filament, as closely as possible and both within a defined location with respect to the focusable area of the reflector of the sun lamp bulb, a pattern of combined, uniformly blended radiations including both ultra-violet and infra-red radiations are thereby produced by the lamp in a well defined and uniform beam.

These and other features of the invention will be best understood and appreciated from the description of the structural details of the mount assembly forming a complete unit of a modern type sun lamp. For purposes of illustrations, the accompanying drawings show this complete and novel mount assembly in which,

Fig. 1 is a view in perspective of a complete sun lamp, portions of the bulb being shown as broken away in order to more clearly illustrate the mount assembly structural details.

Fig. 2 is a view in elevation of the complete sun lamp of Fig. 1, but shown in a position with the two separate sections of the ballast filament directly opposite one another.

Fig. 3 is a view in elevation of the complete sun lamp assembly of Fig. 1 with portions of the bulb being shown as broken away so as to illustrate the two separate sections of the ballast filament, positioned and placed on each side of the mercury arc discharge tube.

Fig. 4 is a circuit diagram of the sun lamp components of Fig. 1, showing the improved mount assembly with respect to the location of the various elements included therein, and describes the function of these elements in operation.

The sun lamp of Fig. 1 is shown as comprising

a bulb 1 of more or less conventional shape and having ultra-violet transmission characteristics, provided with a metallic coating forming a reflector 5 preferably of aluminum, having a cut-off portion ending in a line 1, substantially the line of maximum diameter of the bulb 1. This bulb is provided with a metal lamp screw base 3, which is cemented to the said bulb and has mounted therein, upon the glass stem 11, the improved mount assembly comprising lead wires 13 and 15, metallic platforms 17 and 21, insulated by insulators 23, and affixed in position by eyelets 25, all cooperating to support and position within a predetermined focusable area with respect to the reflecting surface 5 of the bulb 1; an arc tube 27 having spaced electrodes 28 and a starting coil 30 interconnected in series with the ballast filament divided into equal sections 43 and 44. This ballast filament consists of two separate coils 43 and 44 connected in series and supported by the metallic platform 21, the hooks 45, the lead electrodes 48. The coils are positioned parallel to and adjacent the longitudinal axis of the mercury arc discharge tube 27. These two separate sections of the ballast coil filament are each firmly supported in their approximate centers by the glass insulated beads 41, having supports 46 and pigtales 47. Also illustrated in this assembly is a thermostatic switch unit, mounted as an integral part of the supporting platform 17, which supports the mercury arc tube 27 and the ballast filament hook connectors 48.

Fig. 2 is a view in elevation of the lamp of Fig. 1 with portions of the bulb being cut away to more clearly illustrate the improved mount assembly construction previously described in the sun lamp of Fig. 1.

Fig. 3 is another view in illustration of a complete sun lamp, but from a different point of view, showing portions of the bulb being shown as broken away to more clearly illustrate the improved mount assembly of the sun lamp of Fig. 1.

Fig. 4 is a circuit diagram which serves to illustrate the relative positioning of the components of the improved mount assembly, in order to more clearly explain the advantages derived from this improved mount assembly when in operation.

Referring to Fig. 4, when an applied voltage of alternating current is connected to the terminals of the sun lamp base 51 and 53, on one half of the cycle, the current follows the support 13 through one portion of the ballast filament 43, the support hook 45 across the support platform 21, hook support 45 and through the other section of the ballast filament 44, support connector hook 48, flexible lead connection 38, starting coil filament 30, flexible lead connection 39 through junction 42 affixed to the metallic platform 17, to terminal point 37 of the bimetallic thermostatic switch element 29 which has a support arm 31 and a stop arm 40 with contacting members 35 and 33 at contacting point 35. The electrical circuit is complete through the bi-metallic surfaces 31, 29, contact arm 36 at contact point 35 through contacting arm 33, which is affixed to the lead wire 15 and which continues the circuit to the terminal of the base of the lamp 53. When the current is first applied to the lamp, the starting coil which is in the circuit in series with the two sections of the ballast filament and interconnected thereto by the bi-metallic switch, causes heat to be generated within the arc tube as well as ionization of the inert gas content of the tube. Simultaneously, the two sections of

the ballast filament becoming incandescent cause a rapid heating of the mercury vapor tube as well as heating of the thermostatic switch unit, so that it opens and causes the circuit established in the starting coil to be broken. The heating of the mercury vapor, together with ionization of the inert gas in the arc tube 27, facilitates the striking of an arc between the open oppositely disposed electrodes 28, so that an arc discharge is maintained and completes the electrical circuit which is in series with the ballast filament sections 43 and 44.

It has been found by actual test and comparison that the time consumed in achieving the maximum efficiency of a sun lamp is considerably reduced by the use of this new and improved mount assembly. The improvement in this time factor of stabilizing the operational characteristics, considerably improves the efficiency of this type of sun lamp.

The two sections of ballast filament illustrated show a conventional form of coiled tungsten filament being supported in closely spaced relation to the longitudinal axis of the mercury vapor arc tube. However, this filament also may be made of a coiled-coil type of tungsten filament, which materially reduces the length of the filament required. Several adaptations using coiled-coil filaments have been made, and in one particular form a single coiled-coil filament, rather than two separate sections, was used with considerable success. In the case of coiled-coil tungsten filaments, it has been observed that the non-sag qualities of these filaments are desirable. The ballast filament, divided into two or more equal portions, may be connected either in series or in parallel, in order to meet particular circuit requirements. For simplification of assembly and construction, however, it has been found that a single coiled-coil filament operates satisfactorily and with a considerably improved and uniform pattern of heat radiation.

The ultra-violet radiations produced by the mercury arc discharge tube and the infra-red radiations produced by the incandescent ballast filament are thus brought together to a common focusable point with respect to the reflector of the sun lamp bulb. The blending of both of these sources of radiations produces a well defined and uniform beam of improved efficiency, and the degree of infra-red heat radiations within the predetermined focusable area is considerably increased. This is very desirable inasmuch as exposed areas of the body may benefit from the infra-red heat radiations, for maintaining a comfortable degree of warmth when so exposed.

It is important to note that, in the design of this new mount assembly, the ballast filament may require spacing at the extreme limits of the mount assembly, particularly when glass closely similar to quartz is used for the arc tube. The reason for this is that excessive heat as well as possible electrostatic effects tend to cause a devitrification of this glass on at least one portion of its external surface. This devitrification can be reduced to some degree by first thoroughly glazing, or polishing by heating means, or by firing the external surfaces of this glass tube. It has been observed that devitrification is often more pronounced on one side of the glass tube, (the side adjacent to the ballast filament, directly connected to one side of the line). This seems to be due to an electrical phenomenon, and is probably the result of ions from the ballast filament bombarding that particular side of the glass

tube. This action may be retarded somewhat by the use of inert gas filling for the lamp, such as argon-nitrogen mixtures, which have a tendency to reduce the cyclic action of the incandescent tungsten ballast filament. However, the ultimate type of glass that may be used for mercury arc discharge tubes, for generating a high intensity arc having maximum ultra-violet radiation spectra characteristics is pure quartz. This type of glass has negligible characteristics of devitrification.

Having thoroughly disclosed my invention and described the embodiments thereof, but without intending to limit it to the details of construction shown, I claim and desire to secure by Letters Patent:

An electric lamp comprising a base, a bulb having a curved reflecting surface extending outwardly from said base, an elongated cylindrical ultraviolet emitting arc discharge tube disposed along the optical axis of the bulb and extending outwardly from said base in axial alignment therewith, upper and lower metallic platforms forming a portion of the circuit surrounding the end portions of said discharge tube and rigidly supporting the same, a refractory incandescent ballast filament having a plurality of sections,

each filament section being secured at its ends to said platforms and arranged in close parallel relation to said arc tube, each of said filament sections being of sufficient length to span substantially the full length of said arc discharge tube, and a diffusing frosting on the bulb positioned on the end thereof.

MICHEL E. MACKSOUAD.
